Patented Nov. 8, 1966

206,146

SHOESTRING KNOT RETAINER

Charles E. Hendershot, R.R. 4, Nashville, Ind.

Filed May 7, 1965, Ser. No. 85,169

Term of patent 3½ years

(Cl. D7—6)

Fig. 1.

Fig. 2.

Fig. 3.

Fig. 4.

FIG. 1 is a perspective view of a shoestring knot retainer, showing my new design, the broken line showing of a shoe being for purposes of illustration only;

FIG. 2 is a side elevational view of a shoestring knot retainer shown in FIG. 1, the side opposite being a mirror image thereof;

FIG. 3 is a top plan view thereof; and

FIG. 4 is a bottom plan view thereof.

I claim:

The ornamental design for a shoestring knot retainer, as shown and described.
